(57) **CLAIM**

The ornamental design for an autoinjector, as shown and described.

DESCRIPTION

FIG. 1 is a top perspective view of an autoinjector in accordance with the new design;

FIG. 2 is a front elevational view of the autoinjector of FIG. 1;

FIG. 3 is a rear elevational view of the autoinjector of FIG. 1;

FIG. 4 is a right side elevational view of the autoinjector of FIG. 1;

FIG. 5 is a left side elevational view of the autoinjector of FIG. 1;

FIG. 6 is a top plan view of the autoinjector of FIG. 1; and, FIG. 7 is a bottom plan view of the autoinjector of FIG. 1. The broken lines in FIGS. 1-7 illustrate portions of the autoinjector which form no part of the claimed design.

1 Claim, 4 Drawing Sheets
